UNITED STATES PATENT OFFICE

HENRY F. SCHROEDER, OF CLEVELAND, OHIO.

STOP AND WASTE COCK.

1,153,645.

Specification of Letters Patent. Patented Sept. 14, 1915.

Application filed February 5, 1913. Serial No. 746,269.

To all whom it may concern:

Be it known that I, HENRY F. SCHROEDER, citizen of the United States, residing at Cleveland, in the county of Cuyahoga and State of Ohio, have invented certain new and useful Improvements in Stop and Waste Cocks, of which the following is a specification.

This invention relates to an improvement in stop and waste cocks, and the invention consists in a coupling member having a main valve and an independent waste valve located at one side thereof and adapted to control the waste as well as serving other important purposes, all substantially as shown and described and particularly pointed out in the claims.

In the accompanying drawings, Figure 1 is a side elevation of a coupling member partially in section and showing the main valve seated therein and the controlling head of the waste valve. Fig. 2 is a plan view on line 2-2, Fig. 1, showing especially the waste valve and its construction and seat. Fig. 3 is a cross section on a line corresponding to line 3-3, Fig. 2, with the waste down.

Several material advantages are obtained by constructing a waste mechanism as thus shown in connection with the main valve which comprises not only the individual opening and closing of the waste at will without manipulating the main valve but it also provides exceptional means for making repairs on the main valve and for cleaning the opening for the waste valve as well as having a guide in the waste valve for the installation thereof on the right side, all as will hereinafter fully appear.

The main member consists in a union or coupling *c* constructed at its ends internally with screw-threads to make the usual pipe connections and provided at its middle internally with a valve seat *s* and an internally threaded neck *g* opposite said seat in which the externally threaded head *f* of the valve *v* is rotatably engaged. A suitable cap *h* surrounds the said neck and a packing *2* therein about the valve stem *3* prevents possible leakage of fluid about said stem. Of course these features of construction in themselves are not new in compression valves but the novelty resides in the combination of the main valve *v* with the waste valve *4*. The said valve *4* is of the needle or beveled or more or less pointed type seated in the cou-

pling *c* at right angles to valve *v* and at the waste side of said valve in the coupling in the base of a nipple *n* projecting outward from said coupling. The seat for valve *4* is tapered to provide a sharp edge seat for the pointed end of the waste orifice *6*. The space about the said seat is enlarged as compared with the body of valve *4* so as to afford a fluid space about the same, and the stem *m* is screw threaded into the nipple *n* and has a duct *d* centrally lengthwise with an entrance or opening in the head of valve *4* back of its seating portion and discharging through the milled or knurled head *h*. It follows when valve *4* is opened the waste will discharge through the duct or bore *d* in the stem thereof, and the said valve is thus made an independent member adapted to be opened and closed alone and apart from main valve *v*. However, and obviously, the said valves are mutually and operatively related, and the valve *v* controls the flow of water through the coupling while valve *4* controls the waste when said main valve is closed. A half turn of the valve *4* will open the waste sufficiently, and by having an individual valve of this kind it can be easily removed for cleansing the passage, whereas with the old plug type of valve and a waste orifice controlled thereby, the plug itself had to be removed for cleansing and the water had to be turned off the line. Manifest advantage also accrues in the installation of the coupling by having a special waste of this kind, as above noted, the valve *4* being at the side of the main valve helping to locate the waste in the right place.

A horizontal or other position of the joint or coupling *c* may be used. In Fig. 3 the waste is shown at the bottom or down. Usually the waste coupling is so positioned that it is protected from the frost by its position and hence almost any position which a particular location may impose may be safely adopted in placing the joint, whether horizontal or vertical. The waste side or portion of the joint *c* obviously is the one open to the pipe which is exposed to freezing and is to be emptied, while the other side or portion is constantly open to the service pipe.

What I claim is:

1. In stop and waste cocks, a body having a main water passage and valve seat, a valve chamber and a reciprocable valve op-

posite said seat, a waste nipple projecting outward from said body between one end and the transverse median line of said body and in the same plane approximately as the 5 valve seat, and a waste valve for said waste nipple.

2. In stop and waste cocks, a chambered body having opposite ends internally screw-threaded and a valve seat and neck on the 10 transverse median line of said body and a waste nipple projecting from the side of said body at one side of said median line beneath the plane of said valve seat, a valve for said valve seat and a valve stem extending 15 through said neck, and a screw valve for said waste-nipple having a central waste passage and an outer finger-gripping member.

3. In a stop and waste cock, a chambered coupling body having a neck and a main 20 valve seat centrally between its ends and a radially-projecting nipple at one side of the longitudinal median line of said body between one of its ends and the valve seat and beneath the plane of said seat, a reciprocable valve within said neck opposite the main valve seat, and a rotatable screw valve 25 for said nipple to control the flow of waste therefrom.

In testimony whereof I affix my signature 30 in presence of two witnesses.

HENRY F. SCHROEDER.

Witnesses:

E. M. FISHER,
F. C. MUSSON.
